CLAIM

The ornamental design for a battery, as shown and described.

DESCRIPTION

FIG. 1 is a front, top, and left side perspective view of a battery showing our new design;

FIG. 2 is a rear, top, and right side perspective view thereof;

FIG. 3 is a front view thereof;

FIG. 4 is a rear view thereof;

FIG. 5 is a top plan view thereof;

FIG. 6 is a right side view thereof; and,

FIG. 7 is a left side view thereof.

The dash-dash broken lines illustrate portions of the battery that form no part of the claimed design. The dot-dash broken lines illustrate the boundary of the claim and form no part of the claimed design.

1 Claim, 7 Drawing Sheets
